UNITED STATES PATENT OFFICE.

ERNEST HEIDMAN, OF NEW YORK, N. Y.

LOCK.

SPECIFICATION forming part of Letters Patent No. 722,406, dated March 10, 1903.

Application filed November 1, 1902. Serial No. 129,783. (No model.)

To all whom it may concern:

Be it known that I, ERNEST HEIDMAN, a citizen of the United States, residing at New York, in the county of New York and State of New York, have invented certain new and useful Improvements in Locks, of which the following is a specification, such as will enable those skilled in the art to which it appertains to make and use the same.

10 The object of this invention is to provide an improved lock which is simple in construction and operation and which may be applied to a door, gate, hinged window, or other device of this class and which is provided with 15 a key of special construction by which it may be operated; and with this and other objects in view the invention consists in a lock and key of the class specified constructed as hereinafter described and claimed.

20 The invention is fully disclosed in the following specification, of which the accompanying drawings form a part, in which the separate parts of my improvement are designated by suitable reference characters in each 25 of the views, and in which—

Figure 1 is a front view of my improved lock applied to a door or a part thereof; Fig. 2, a side view thereof; Fig. 3, an inside view of the lock-casing with the back plate removed; Fig. 4, a section on the line 4 4 of Fig. 3; Fig. 5, a section on the line 5 5 of Fig. 3; Fig. 6, a side view of a key which I employ; Fig. 7, an outside end view of a key bushing or casing connected with the lock-casing and through which the key in the operation thereof is passed, the key being shown therein with the outer end thereof broken away; Fig. 8, a similar view of a part of the lock in connection with which the end of the 40 key operates; Fig. 9, a section on the line 9 9 of Fig. 6, and Fig. 10 a section on the line 10 10 of Fig. 6.

In the drawings forming part of this specification I have shown at *a* a part of a door, 45 and in the practice of my invention I provide a lock comprising a main casing *a*² and a back plate *a*³, and said back plate is provided with a key bushing or casing *a*⁴, which passes through the door in the form of construction 50 shown and through which in operation the

key *b* is adapted to be inserted. It will be understood that the casing is secured to the inner side of the door, and the main part *a*² thereof is provided with a longitudinal slot or opening *a*⁵, having at its rear end a downwardly-directed extension *a*⁶, and mounted on the main casing *a*² is a knob *c*, having a shank *c*², which passes inwardly through the slot *a*⁵ and is provided at its inner end with a cross-head *c*³. The main casing is also provided with two bolts *d*, which pass through a keeper *d*², to which are secured springs *d*³, which are also connected with the inner ends of said bolts at *d*⁴, and said bolts are provided with the usual beveled heads *d*⁵, which pass 65 through the face of the main casing *a*² of the lock and are adapted to engage the catch-plate *d*⁶, secured to the door-frame in the usual manner and as indicated in Fig. 5, a part of the door-frame being shown at *d*⁷. 70 Each of the bolts *d* is also provided with an inwardly-directed pin *d*⁸, in connection with which the cross-head *c*³ operates, and by moving the knob *c* longitudinally and backwardly the cross-head *c*³ will operate in connection 75 with the pins *d*⁸ to force the bolts *d* backwardly, and when the knob *c* is at the limit of its backward movement it is pressed downwardly, so that the neck *c*² thereof enters the downwardly-directed extension *a*⁶ of the slot 80 *a*⁵, and the bolts *d* are locked in their rear-most position, and the door may be opened and closed, as will be readily understood.

Secured to the inner side of the main casing *a*² or formed integrally therewith is a 85 block *e*, on which is pivoted at *e*² an arm *e*³, provided with a longitudinal slot *e*⁴, in which works a pin *e*⁵, secured to the bottom bolt *d*, and the arm *e*³ is provided in line with the pivot-point *e*² with a cylindrical projection *e*⁶, 90 on which is mounted a supplemental arm *f*, provided with a slot *f*², which receives a pin *f*³, secured to the upper bolt *d*, and said arms *e*³ and *f* range transversely of said bolts, the arm *e*³ extending across the lower bolt *d* and 95 the arm *f* across both of said bolts, and said arm *f* is also provided with a circular head *f*⁴, through which the cylindrical projection *e*⁶ of the arm *e*³ passes.

I also provide a key *b*, comprising a head 100

b^2 and a flat metal shank b^3 , the end of which is provided with oppositely-directed edge-wings b^4 , which, together with the shank b^3 , are cut off at the corners, as shown at b^5 , so 5 as to provide a central projection b^6 and two side projections b^7 . The central projection b^6 is adapted to enter a corresponding recess g in the cylindrical projection e^6 , and the side projections b^7 are adapted to enter corresponding recesses g^2 in the head f^4 of the arm f , said recesses being clearly shown in Fig. 8, where they are provided with reference-letters, and being also shown in Fig. 4 with the key or the parts thereof in position. The outer 10 end of the bushing or casing a^4 is provided with an N-shaped slot or recess g^3 , and the shank b^3 of the key is provided adjacent to the head b^2 thereof with side wings g^4 , and the shank of the key is provided at this point 15 with a transverse slot or opening g^5 , and the wings g^4 are cut out transversely to form corresponding notches or recesses g^6 . It will be seen that wings b^4 at the end of the shank of the key are of the same form as the wings g^4 , 20 and in practice the key is passed inwardly through the bushing or cylindrical casing a^4 , and the projections b^6 and b^7 at the end thereof engage with the corresponding recesses g and g^2 in the cylindrical member e^6 of the arm e^8 25 and the head f^4 of the arm f , and in this operation the wings g^4 also pass into the outer end of the bushing or casing a^4 , as shown in the drawings, and in this position of the parts the key may be partially turned, or through 30 an arc of ninety degrees, the position of the key when so turned being indicated in Fig. 7, in which the outer end of the key is broken away. In this operation the arms e^8 and f are both turned backwardly, and the bolts d 35 are correspondingly operated, and the door will be unlocked, as will be readily understood, and when the pressure on the key is removed or the said key is turned in the opposite direction the springs d^3 operate so as to again project said bolts.

It will be understood that my improved lock is intended principally for a night-lock and to be used in connection with an ordinary lock in the usual manner; but it will also be 40 understood that my improved lock may be used wherever a device of this class is desired. It will also be understood that when the knob c is in the position shown in Fig. 3 the door will be locked, and the door may be 45 unlocked by manipulating the knob c from the inner side of the door whenever desired, and the bolts d may be secured in the open or withdrawn position, in which the door may be opened and closed without reference to 50 the lock, or whenever it is desired to use the key for the purpose of securing or locking the door the knob c must be placed in the position shown in Fig. 3, and the door may then be unlocked from the outer side by means of 55

the key, or it may be unlocked from the in- 65 side by means of the knob c .

Having fully described my invention, what I claim as new, and desire to secure by Letters Patent, is—

1. A lock comprising a main casing and a 70 back plate having a key bushing or casing through which a key may be inserted, said main casing being provided with two spring-projected bolts, a knob mounted on the main casing and provided with a shank which 75 passes through a longitudinal slot formed therein and the rear end of which is provided with a downwardly-directed extension, said shank being provided at its inner end with cross-heads and said bolt with pins in connection with which said cross-heads operate, and two pivoted arms arranged transversely of 80 said bolts and provided with longitudinal slots through each of which a pin connected with one of said bolts passes, and a key adapted to be passed through the key bushing or casing and operate said arms, substantially 85 as shown and described.

2. A lock of the class described provided with two spring-bolts, two pivoted arms de- 90 signed to operate said bolts one of said arms being provided with a head and the other with a cylindrical projection which passes therethrough, said head and said projection being provided, the first with two recesses and the 95 second with a transverse recess, and a key the shank of which is provided with oppositely-directed wings, said shank and said wings being cut away to form three projections adapted to enter said recesses, substan- 100 tially as shown and described.

3. A lock of the class described provided with a key bushing or casing, two spring-bolts and two pivoted arms designed to operate said bolts one of which is provided with a head and 105 the other with a cylindrical projection which passes therethrough, said head being provided with two recesses and said projection with one recess, the key bushing or casing being also provided at its outer end with an N- 110 shaped slot or opening, and a key the shank of which is provided at the end thereof with side wings which project in opposite directions, said shank and said wings being cut away to form three projections adapted to 115 enter said recesses, and the said shank of the key adjacent to the head thereof being also provided with oppositely-directed wings and with a central transverse opening, and said wings being also cut away centrally to form 120 recesses, substantially as shown and described.

4. In a lock of the class described a casing, two spring-projected bolts mounted therewith, two arms pivoted in said casing and arranged transversely of said bolts, each of said arms being provided with a longitudinal slot, pins connected with said bolts and passing 125

through said slots, a knob for operating said bolts from the inner side of the door against the action of the springs connected therewith, and a key for operating said arms so as to operate said bolts against the action of said springs, substantially as shown and described.

In testimony that I claim the foregoing as

my invention I have signed my name, in presence of the subscribing witnesses, this 27th day of October, 1902.

ERNEST HEIDMAN.
